DESIGN FOR A RADIO RECEIVER CABINET

John R. Morgan, Mount Prospect, Ill., assignor to
Sears, Roebuck and Co., Chicago, Ill., a cor-
poration of New York

Application September 19, 1940, Serial No. 95,219

Term of patent 7 years

To all whom it may concern:

Be it known that I, John R. Morgan, a citizen of the United States of America, residing at Mount Prospect, in the county of Cook and State of Illinois, have invented a new, original, and ornamental Design for a Radio Receiver Cabinet, of which the following is a specification, reference being had to the accompanying drawing, forming a part thereof.

Figure 1 is a front perspective view of a radio receiver cabinet embodying my new design; and Figure 2 is a rear perspective view of the same.

I claim:

The ornamental design for a radio receiver cabinet, substantially as shown.

JOHN R. MORGAN.
